UNITED STATES PATENT OFFICE.

DANIEL ROUNDS, OF PORTLAND, MAINE.

REPAIR-JACK.

1,103,844.

Specification of Letters Patent. Patented July 14, 1914.

Application filed September 12, 1912. Serial No. 719,903.

To all whom it may concern:

Be it known that I, DANIEL ROUNDS, a citizen of the United States, residing at Portland, in the county of Cumberland and State of Maine, have invented certain new and useful Improvements in Repair-Jacks, of which the following is a specification.

This invention relates to improvements in shoemakers' repair jacks. These usually consist of a pedestal upon which is mounted a last supporting device which is rotatable in both horizontal and vertical planes. In jacks as at present constructed, when the last supporting device is turned in a vertical plane in either direction, the last is carried very much below its normal position, thus making the jack vary greatly in height from the floor and in that respect rendering it inconvenient for the workman.

In the drawing herewith accompanying and making a part of this application, Figure 1 is a side elevation of my improved repair jack; Fig. 2 is a side elevation of the same when the last holder is tipped into horizontal position, showing the underside of the table, a portion of the pedestal being removed; Fig. 3 is a vertical sectional detail showing the ring, strap carrier and plate upon which the ring and carrier are mounted; and Fig. 4 is a plan view of the ring, strap carrier and means for locking the strap carrier to the ring.

Same reference characters indicate like parts in the several figures.

The object of the present invention is to provide a jack in which the last supporting device, when turned in a vertical plane, is automatically caused to rise as it is turned, compensating in large measure for the downward movement due to the vertical turning. It is also designed to provide an inexpensive, easily operable repair jack. To this end, it consists of a pedestal A terminating at the top in bifurcated supporting arms B.

Rotatably mounted upon a bar E rigidly set in these arms is a table C provided in the top with grooves or channels P' to serve to lessen the weight of the machine and with ears D through which the bar passes. One of the ears D is provided with a series of ratchet teeth F and the table is adapted to be locked against vertical turning by means of a vertically reciprocating locking pin G, which is normally held up against said ratchet teeth by a spring H, the upper end of the spring being made fast to the pin

shank. The lower end of the pin is connected to a foot treadle I by means of a connecting link or chain K. Superposed upon the table C is a plate L which is secured to table C by means of headed bolts M secured to the underside of the plate and passing through slots N in the table. On the underside of plate L are one or more transversely extending racks O and upon shaft E are gears P adapted to project upwardly through slots Q in the table C and to mesh with the teeth in racks O in the plate L. Secured to plate L and adapted to rotate in a plane parallel therewith is a ring R upon which is set at one end a toe support S and at the other end a heel support T. The mechanism shown for securing ring R to plate L is new and a part of my invention.

The plate L is provided with an upraised rib V spaced apart from the edge forming a ledge U upon which the ring R is mounted and against the raised part V of which the ring revolves. The ring is held in place by a keeper U' set on the top of the part V which keeper overlaps the inner edge of the ring, thus holding it in place upon plate L. The heel support is pivotally attached to a post X set on the ring and is adjustable by means of a threaded bolt Y. The toe support is longitudinally adjustable in a vertically slotted post Z mounted on said ring and may be locked in any given place by a set screw Z'. To hold the last on the jack, I provide a strap 1 adapted to pass over the last and through a rotatable carrier 2 set in the top of plate L and held in place preferably by the keeper U' which holds the ring upon plate L. The carrier is provided with two slots 3 through which the strap passes, the central part of the under side of the carrier being countersunk, as seen at U² to give space for the strap to pass freely between the top of the plate L and the bottom of the carrier.

The carrier may be locked against accidental rotation by means of a spring pawl 4 pivotally attached to the carrier and adapted to take into a series of indentations 5 in the ring, whereby the carrier normally moves with the ring but may be adjusted relative to the ring to tighten the holding strap by raising the pawl and rotating the carrier.

The operation of my improved jack is as follows: The last with its shoe is placed upon the jack when the supports are in ver-

tical position which may be called the normal position of the machine. It may then be rotated in a horizontal plate by turning the ring on the supporting plate. It may 5 also be turned in a vertical plane so that the supports are at right angles to said normal position on either side of the machine when work is to be done on either side of the shoe and while in this latter position the ring 10 may be rotated but now in a vertical plane. As the holding mechanism is being turned to right angles from the normal position, the ring and plate are caused to travel upwardly relative to the table by reason of the 15 gears on the shaft meshing with the teeth in the bottom of the plate.

Having thus described my invention and its use, I claim:

1. In a repair jack, a pedestal, a work 20 support mounted on said pedestal and arranged to have rotary motion about both horizontal and vertical axes, and means for automatically causing the work support to rise or fall in response to the turning movement of the work support about its horizontal axis.

2. In a repair jack, a pedestal, a work support mounted in said pedestal and arranged to have rotary motion about both 30 horizontal and vertical axes, and means for automatically causing said work support to rise or fall with a graduated regular motion in response to the turning movement of the work support on its horizontal axis.

3. In a repair jack, a pedestal, a table 35 mounted on said pedestal adapted to have vertical rotation, a plate mounted on said table and adapted to have sliding movement relative thereto, and a work supporting 40 ring mounted on said plate and adapted to be rotated relative to said plate.

4. In a repair jack, a pedestal, a table pivotally supported on said pedestal, a plate 45 mounted on said table and adapted to have sliding movement relative thereto, means for causing said plate to slide on said table when the table is rotated, and a work support mounted on said plate.

5. In a repair jack, a pedestal, a shaft 50 fixedly mounted in said pedestal, a table rotatably secured to said shaft and provided with a slot, a plate adapted to have sliding movement relative to said table, a gear rigidly secured on the shaft, a rack on the under side of the plate, the gear on the shaft being adapted to project through the slot in 55 the table into engagement with the rack on the under side of the plate, and a work support mounted on said plate.

6. In a repair jack, a pedestal, a table 60 mounted on said pedestal arranged to have rotation about a horizontal axis, a plate on said table and adapted to have sliding movement relative thereto, a work supporting ring mounted on said plate and adapted to be rotated relative to said plate, a work 65 holding strap carrier, and means for locking the strap carrier to the supporting ring.

7. In a repair jack, a pedestal, a table 70 mounted on said pedestal arranged to have rotation about a horizontal axis, a plate 75 mounted on said table and adapted to have sliding movement relative thereto, a work supporting ring mounted on said plate and adapted to be rotated relative to said plate, and a rotatable work holding strap carrier mounted on said plate, said strap carrier being manually rotatable independently of said ring.

8. In a repair jack, a pedestal, a table 80 mounted on said pedestal arranged to have rotation about a horizontal axis, a plate 85 mounted on said table and adapted to have sliding movement relative thereto, a work supporting ring mounted on said plate and adapted to be rotated relative to said plate, a rotatable work holding strap carrier 90 mounted on said plate, said strap carrier being manually rotatable independently of said ring, and means for locking the strap carrier in any desired position.

DANIEL ROUNDS.
